UNITED STATES PATENT OFFICE

GIDEON SUNDBACK, OF MEADVILLE, PENNSYLVANIA, ASSIGNOR TO HOOKLESS FASTENER COMPANY, OF MEADVILLE, PENNSYLVANIA, A CORPORATION OF PENNSYLVANIA

FASTENING DEVICE

Application filed December 14, 1929. Serial No. 414,158.

My invention relates to fastening devices and particularly to that class of such devices which comprises opposed series of fastener elements adapted to be progressively interlocked by being brought together successively at an angle to each other.

One of the objects of my invention is to provide an improved construction of the fastener elements so that they can be quickly and cheaply manufactured.

Another object of my invention is to provide an improved fastener construction of the type in which each interlocking element comprises a small length of wire bent to the desired shape.

Other objects and advantages of my invention will hereinafter more fully appear.

In the accompanying drawings, I have shown for purposes of illustration two embodiments which my invention may assume in practice. In these drawings:

Fig. 1 is a plan view of a fastener embodying my invention with a part of the slider broken away.

Fig. 2 is a view illustrating the manner in which the parts of a stringer of my improved fastener are assembled.

Fig. 3 is a sectional view on line 3—3 of Fig. 2.

Fig. 4 is a longitudinal central section on line 4—4 of Fig. 1 through a portion of my improved fastener showing the method of interlocking.

Fig. 5 is a transverse section similar to Fig. 3 showing a modified construction.

Fig. 6 is a central longitudinal sectional view similar to Fig. 4, showing a fastener made according to the modified construction.

Figs. 7, 8 and 9 are views of the wire blank illustrating steps of the process of forming a fastener element of the modified construction shown in Figs. 5 and 6.

The fastening device of the type to which my invention relates usually comprises a pair of flexible stringers which, in the drawings, are designated 11 and 12 and a series of spaced fastener elements secured to the adjacent edges of said stringers. A slider 13 is usually employed to bring the fastener elements together successively at an angle

to each other and the slider illustrated comprises a pair of overlying spaced wings positioned on opposite sides of the stringers and having a Y-shaped channel through which the fastener elements pass during the travel of the slider. The overlying spaced wings are connected at the rear end by an integral wedge portion which causes separation of the fastener elements when the slider is moved in one direction. The slider is operated by a pull device 13 pivotally connected to the slider the connecting means not being shown in the drawings. Each of the stringers 11 and 12 comprises a relatively hard cord or wire 14 to which is secured a series of spaced wire fastener elements 15 and a fabric tape 16 doubled over the cord 14. The tape 16 is provided with a series of apertures 17 to receive the fastener elements 15 and these apertures are preferably formed by leaving out certain of the warp threads in the central portion of the fabric leaving the two sides connected together only by the weft threads. The tapes 16 provide suitable means for connecting the fastener to an article to be fastened.

Each of the interlocking elements in the preferred form is made by bending a round wire to substantially a U-shape providing parallel side portions 18 and 19 connected together by the bent portion 20. The ends of the bent wire project outwardly from the stringer and one of such ends is longer than the other and is bent back upon itself and upwardly at an angle to provide the interlocking projection 21 which is positioned between the side portions 18 and 19. The portion forming the projection 21 is preferably bent at an angle of about 45° and such bending brings the end surface 22 of the wire also to an angle of about 45° and this end surface as seen in Fig. 1 abuts against the under side of a bent end portion 21 on an adjacent fastener element of the opposite series and projects between the side portions 18 and 19 of such element. In bending the wire around the cord 14, the cord is compressed so that the fastener elements are held securely against displacement along the stringer. In practice, there will be a certain amount

of longitudinal clearance provided between the fastener elements as seen in Figs. 4 and 6 so as to make the fastener sufficiently flexible transversely of the stringers. Thus it 5 may be freely bent to take the shape of the article to which it is attached and still remain securely interlocked.

In the modification illustrated in Figs. 5 to 9 inclusive the construction is substantially 10 the same except that the inner surfaces of the side portions 18 and 19 are flattened as indicated at 23 and 24 to provide two parallel flat surfaces for receiving the interlocking projections 21 of adjacent fastener elements.

15 In making this type of fastener element a straight wire blank 25 has one end offset as shown at 26 in Fig. 9. In the strip as illustrated in Figs. 7 and 8 this wire is rolled to provide a flat surface 27 extending to the 20 offset portion and when the wire is doubled over as in Fig. 5 the flat surface 27 forms the parallel surfaces 23 and 24.

In operation, the opposed series of fastener elements are brought together in the 25 manner illustrated in Fig. 1 by means of the slider 13. When they approach each other at an angle, the ends of the elements ride over one another and the interlocking projections 21 fall into the spaces between the 30 side portions of adjacent fastener elements. If a pull is exerted on the opposite sides of the fastener, the end surfaces 22 will abut against the under side of the bent end portion of an adjacent fastener element and by 35 the cumulative action of the whole series of elements, the fastener is held securely in fastened condition. When it is desired to open the fastener, the slider is operated in the reverse direction and the entering wedge 40 spreads the fastener elements apart and causes them to be progressively unlocked.

45 As a result of my invention, it will be apparent that a novel fastener construction has been provided which can be easily and cheaply manufactured. Each of the fastener elements simply requires a short length of wire to be bent up to the desired shape and assembled in a stringer with other like elements. The fastener elements on both 50 stringers are alike which tends further toward low cost of manufacture.

While I have in this application specifically described two embodiments which my invention may assume in practice it will be 55 understood that these forms are merely for the purpose of illustration and description and that various other embodiments may be devised within the scope of my invention as defined in the appended claims.

60 What I claim as my invention is:

1. A fastener comprising a pair of flexible stringers, rows of cooperating fastener elements secured to said stringers, each of said elements comprising a strip of wire bent upon itself in a plane transverse to said stringers

and having one end bent up between said bent portions out of said plane to provide means for interlocking with the elements of the other stringer.

2. A fastener comprising a pair of flexible 70 stringers, rows of cooperating fastener elements secured to said stringers, each of said elements comprising a strip of metal bent in a plane transverse to said stringers to provide parallel spaced portions, one end of said strip being bent up from said plane and at an angle thereto and between said portions to provide means for interlocking with the elements on the opposite stringer.

3. A fastener comprising a pair of flexible 80 stringers, rows of cooperating fastener elements secured to said stringers, each of said elements comprising a strip of metal bent upon itself in a plane transverse to said stringers, one of the ends of said strip projecting free from said stringer and being bent backwardly and at an angle to said plane to constitute interlocking means for cooperation with the elements on the opposite 90 stringer.

4. A fastener comprising a pair of flexible stringers, rows of cooperating fastener elements secured to said stringers, each of said elements comprising a strip of round wire bent in a plane transverse to said stringers to provide spaced portions, one end of said wire being bent up from said plane and at an angle thereto between said portions to provide means for interlocking with the elements on the opposite stringer.

5. A fastener comprising a pair of flexible stringers, rows of cooperating fastener elements secured to said stringers, each of said elements comprising a strip of wire bent around one of said stringers and having its ends projecting outwardly therefrom, one of said ends being bent between said portions and upwardly from the plane of such portions to provide means for interlocking with an element on the opposite stringer.

6. A fastener comprising a pair of flexible stringers, rows of cooperating fastener elements secured to said stringers, each of said elements comprising a strip of wire bent upon itself in a plane transverse to said stringers and having one end bent up from said plane and at an angle thereto, the end surface of such end abutting against a bent portion on a similar member of the opposite stringer.

7. A fastener comprising a pair of flexible stringers, rows of cooperating fastener elements secured to said stringers, each of said elements comprising a strip of wire bent upon itself to provide parallel spaced portions, one end of said wire being bent up from the plane of said parallel portions and at an angle thereto to project between parallel portions of a like element on an opposite stringer to interlock therewith.

8. A fastener comprising a pair of flexible stringers, rows of cooperating fastener elements secured to said stringers, each of said elements comprising a strip of wire bent upon itself to provide spaced outwardly extending portions one end of the wire being bent between such portions and at an angle of substantially 45° to the plane of such portions to project between the spaced bent portion of a similar member on the opposite stringer.

9. A fastener comprising a pair of flexible stringers, rows of cooperating fastener elements secured to said stringers, each of said elements comprising a strip of wire bent upon itself to provide parallel spaced portions, one of the ends of such wire being bent between said portions and upwardly from the plane of such portions and a tape having 20 apertures therein folded around said stringer with said elements projecting through said apertures.

10. A fastener comprising a pair of flexible stringers, rows of cooperating fastener elements secured to said stringers, each of said elements comprising a strip of substantially round wire having one side thereof flattened, said wire being bent upon itself with said flat sides facing each other to provide parallel spaced portions disposed in a plane perpendicular to said stringers, one end of each of said wires being bent upwardly from said plane and backwardly at an angle thereto so as to project into the space between the 35 flat sides on a similar element of the opposite stringer.

In testimony whereof I affix my signature.
GIDEON SUNDBACK.
